A. L. ROHRBACHER, JR.

MOLDER'S SHOE

Filed June 14, 1924

Inventor:
A. L. Rohrbacher, Jr.

by Geo. N. Gorlitz, Atty.

UNITED STATES PATENT OFFICE.

ALBERT L. ROHRBACHER, JR., OF BOSTON, MASSACHUSETTS.

MOLDER'S SHOE.

Application filed June 14, 1924. Serial No. 719,945.

This invention relates to shoes, and is particularly intended for use by molders in foundries and elsewhere where the workmen are exposed to the danger of spilling molten metal into their shoes, thereby rendering highly important not only that the maximum of protection should be afforded against the entrance of the metal to the interior of the shoe, but also to make provision for instant removal of the shoe to minimize the injury from such accident.

The present invention is intended to meet these requirements and consists essentially in a shoe whose top or upper portion is vented to form flaps, one overlapping the other, the flaps being provided with interlocking fastening devices on the snap fastener principle, arranged so as to permit the quick detachment or stripping away of the outer flap from the inner one by a downward pull, while resisting strains in a lateral or in an upward direction. Another feature of the invention consists in riveting or fastening the male members of the stud of the snap fasteners to a separate attaching strip which is then sewed on the inner flap of the shoe-top so that the fastener does not penetrate the inner layer of the leather, and in this way I avoid producing objectionable and painful pressure upon the foot by the metallic fastener.

These and other features of the invention will be pointed out in the following specification and will be defined in the claims hereto annexed.

In the accompanying drawings I have illustrated a preferred form of construction and arrangement embodying the principles of this invention, in which:

Figure 1 shows, in elevation, the shoe embodying my improvement exposing the inside face of the shoe to view.

Figure 2 is a cross section through the inner flap of the shoe-top, showing the fastening stud secured in place by the attaching strip.

Figure 3 is a side elevation of the outer flap which carries the spring-containing socket elements of the fastening device.

According to the illustration in the drawings, the shoe-bottom 1, and the vamp 2 are of any usual or suitable construction. The shoe-top or ankle-surrounding portion of the shoe-upper is made with a sufficient circumferential measurement or girth to provide, along the inside portion in front of the

ankle, an opening or vent extending downwardly from the top with one edge, preferably the front edge, considerably overlapping the other edge of the top. This forms 60 overlapping flaps at the vent or fly opening on the side of the shoe to which the co-acting elements of the fastening devices, respectively, are secured.

The male fastening element comprises an 65 angularly grooved stud 5 which is preferably passed through and riveted, or otherwise secured, to an attaching strip 4, which is itself thereafter secured to the inner flap of the vent in any suitable manner, as by say a row 70 of stitches 4a.

The socket member 6, comprises a shallow centrally perforated casing within which is held the wire spring 6a, formed in the shape of a loop extending around the interior of 75 the shallow casing with its free ends 6b extending downward through the middle portion of the casing and under such spring tension as to normally press toward each other. Near the free ends 6b, the arms of the wire 80 are formed to produce an elongated opening 6c, starting from near the upper end of the casing and extending beyond the stud-receiving opening formed at its center, as shown in the lower fastener of Figure 1. 85

This brings the stud-opening opposite the lower end of this elongated space so that, when the pointed end of the stud 5, is forced between the spring jaws or arms, they yield sufficiently to allow the head of the stud to 90 pass through and then contract into the annular groove of the stud. As shown in Figure 1 the stud, when held between the pinching jaws, is, therefore, located in the lower portion of the elongated space formed by 95 the separated portion of the jaws so that the head of the stud overhangs the inwardly turning free ends of the wire. The consequence is that any pull from below or from either side of the stud is strongly resisted 100 by the overhanging head. On the other hand, the open space between the wire jaws on the opposite or upper side of the stud allows the upper end of the outer fastening element to swing outwardly since this side of the 105 head does not overhang the wire and, therefore, the head acts as a wedge to force apart or open the jaws sufficiently to allow disengagement of the wire from the annular groove.

As shown in the drawings the open or releasable side, or if we consider the direction

of the spring jaws as constituting the longitudinal axis of the stud-receiving elements, the releasable ends of the stud-receiving and locking elements all face upward in substantially the same direction, that is, substantially parallel with the direction of the vent itself so that a single outward pull at the top of the outer flap instantly releases or strips the outer flap from the inner one.

10 It will therefore be seen that the direction of setting of the fastening device is important, the essential requirement being that the fastening elements be set to resist all strains that may be exerted by the foot inside the shoe and yet allow the vent to be opened practically instantly by an outward and downward pull on the tab end 3° of the outer flap.

15 It will be understood that I make no claim 20 in this application to the fastening stud per se, but the provision of the shoe flaps of the vent with a quick detachable fastener that is opened or disconnected only by an outward pull from the top is an important 25 feature of the present invention because it insures against the accidental opening of the vent under any strains or stresses that the shoe is subjected to by the foot inside and yet allows the instantaneous opening of the 30 vent from the top by a simple outward pull.

What I claim is:

1. In a molder's shoe the combination with 35 a shoe upper top formed with a vent extending downwardly whose side edges form overlapping flaps, the inner flap being provided with a plurality of properly spaced outwardly projecting studs, and the outer flap being provided with a correspondingly arranged series of coacting stud-receiving 40 fasteners formed to interlock with the studs so as to prevent disengagement therefrom under the lateral and upward stresses of the foot, while readily released by a single outward pull exerted at the top of said outer flap, substantially as described.

2. In a molder's shoe the combination of 50 a shoe upper top formed with a vent extending downward from its top edge, and dimensioned to form overlapping flaps to close said vent, the inner and the outer flaps being provided with cooperating interlocking fastener elements each arranged to register with its coacting element when the vent is closed, said elements being releasable from 55 their locked engagement only by a single outward pull exerted on the outer flap from

above the location of the fasteners, substantially as described.

3. In a molder's shoe the combination with 60 a shoe upper top having a vent opening extending downwardly from the top on one side of the medial line with overlapping flaps, a series of snap fastener elements 65 cooperatively arranged on the respective flaps and comprising, respectively, a row of studs and a row of registering stud-receiving and locking members adapted to open in one direction only for release from the studs, said stud-receiving members having their 70 releasable ends facing upward in substantially the same direction so that a single pull outwardly at the top serves to instantly strip the outer flap from its fasteners, while said fasteners resist release from lateral strains transversely of the vent, substantially as described.

4. A molder's shoe embracing in combination a shoe upper top provided with a vent 75 extending downwardly from its upper edge and dimensioned to form overlapping flaps 80 normally closing the vent, coacting series of interlocking fastener elements secured to the respective flaps, the inner fastener elements penetrating and being secured to a 85 separate strip of material that is secured to the outside face of said flap by stitching to avoid piercing the flap itself, the outer flap having its upper end extending sufficiently beyond the topmost fastener to form a tab 90 adapted to be grasped by the hand, said fastener elements being releasable from interlocked engagement by a single outward pull on said tab while preventing the pressure of the enclosed foot from effecting such 95 disengagement.

5. A molder's shoe embracing in combination a downwardly vented shoe upper top 100 dimensioned to form overlapping flaps to close said vent, a series of outwardly projecting fastener studs secured to the inner imperforate flap by means of an attaching strip secured on the outside of said flap, a registering series of stud-receiving fastener elements secured to the outer flap and arranged to be released from interlocking engagement with said studs only by an outward pull exerted on the upper end of the outer flap above the fasteners, substantially as described.

105 In witness whereof, I have subscribed the above specification.

ALBERT L. ROHRBACHER, Jr.
